UNITED STATES PATENT OFFICE

FREDERICK OSANN, OF WHITE PLAINS, AND RAYMOND L. PLUMLEY, OF BROOKLYN, NEW YORK, ASSIGNORS TO FREDERICK OSANN COMPANY, OF NEW YORK, N. Y., A CORPORATION OF NEW YORK

PORTABLE SEWING MACHINE CARRYING CASE

Application filed May 21, 1929. Serial No. 364,713.

The present invention relates to portable electric sewing machines and particularly to the containers or cases in which such machines are carried. The object of our invention is to provide an improved construction of a carrying case particularly adapted for the transportation of a portable electric sewing machine and characterized by simple and effective provisions for aiding in initially placing and maintaining the machine in a predetermined position in the case, in which position the machine, and particularly the mechanical parts thereof, are effectively protected from ordinary impact stresses.

15 The various features of novelty which characterize our invention are pointed out with particularity in the claims annexed to and forming a part of this specification. For a better understanding of the invention, however, and the advantages possessed by it reference should be had to the accompanying drawing and descriptive matter in which we have illustrated and described a preferred embodiment of the invention.

20 25 Of the drawing:

Fig. 1 is a vertical section through the case showing the machine and tray in position;

Fig. 2 is a section on the line 2—2 of Fig. 1; and

30 Fig. 3 is a section on the line 3—3 of Fig. 1.

In the drawing, we have illustrated a preferred embodiment of our improved carrying case in which the case comprises a rectangular body portion A having a flat bottom member

35 A', vertical front and rear side members A² and A³, respectively, and vertical end members A⁴ and A⁵, respectively. The case body is internally reinforced at its corners by cleats B of substantially triangular cross-section.

40 45 The cleats extend vertically from or adjacent to the bottom A' to a point adjacent to, but preferably below, the upper ends of the side and end members, to which they are secured in any suitable manner.

50 55 A cover or lid C is hingedly connected to the case body by hinges D located at spaced points along the rear side of the case. The cover is preferably formed by a rectangular top plate C' and short vertical side and end plates C² and C³, respectively, connected to

one another and to the top plate C'. The front plate C² of the cover is arranged to be detachably connected to the front side A² of the body by locking latch means E of a well known type mounted along the line of contact at the front of the case. The body and cover portions of the case heretofore described are made of wood or other material having the necessary strength and lightness with an outer cover of washable material, such as "leatherette". A handle F is secured to the upper side of the top plate C', as shown in Figs. 1 and 2.

The portable electric sewing machine with which our improved carrying case is especially adapted for use is of the type disclosed and illustrated in the pending application of Richard K. Hohmann, Serial No. 242,368, filed December 24, 1927 and as shown in the drawing comprises a substantially rectangular base board G on which the machine frame H and electric driving motor are mounted. The machine frame comprises a bed H' symmetrically positioned within and slightly spaced from the periphery of the base board, a standard H² rising from one end of the bed and an arm H³ supported by the standard and terminating at its free end in a head H⁴. The sewing machine working mechanism is mainly contained within the frame casting. One end of the hook shaft J of the mechanism projects beyond the bed portion of the frame casting and carries a belt wheel J' through which the hook shaft is driven from the motor shaft J² at the rear thereof. A flat spool plate K and vertical post K' are mounted on the upper end of the standard as shown. The hollow head H⁴, within which a portion of the needle bar actuating mechanism is contained, extends above and below the arm H³ on which it is supported.

One embodiment of portable electric sewing machine of the type described and constructed with frame casting of aluminum alloy weighs less than thirteen pounds. This material decrease in weight from prior constructions is one of the characteristic features of the machine and its consequent portability makes it particularly in demand for domestic use. In storing and transporting the machine

it is necessary that the mechanism be protected from external forces, and particularly sudden impact stresses. In carrying out this object of my invention the body of the case is provided with a cleat M extending transversely of the end A⁴ of the body at a point adjacent the bottom A'. The lower side M' of the cleat is concavely curved to receive and contact with the correspondingly curved end 10 of the base plate G. The upper end of the cleat curved portion is arranged to fit over the base board sufficiently to prevent direct vertical movement of that end of the machine. The lower ends of the corner cleats B at that 15 end of the case terminate at points spaced sufficiently from the bottom plate or are cut away in such a manner as to receive the corner portions of the base board.

At the opposite end of the case is positioned a block N secured to the bottom A' and lower end of the side A⁵. The block is spaced from the front and rear sides of the case and arranged to contact with the adjacent end of the base board to hold the machine with the 20 opposite end of the base board in contact with and beneath the cleat M. The inner and upper exposed portions of the block N are convexly curved as shown for a purpose hereinafter described. The block N extends inwardly sufficiently to prevent the belt wheel 25 J' from contacting with the adjacent end member of the case when the machine is in the desired position. In placing the machine in the case the left end of the machine is tilted 30 downwardly until that end of the base board is fitted within the recess in the cleat M, the curved upper surface of the block N acting during this movement to force the machine into this position by a camming action. Longitudinal movement of the machine in the case 35 is prevented by the joint action of the cleat and block and lateral movement eliminated by a cleat O extending along the front edge of the case bottom A'.

40 A rectangular tray P is mounted in the upper portion of the case and arranged with a series of separate compartments P' in which the various attachments and accessories used in connection with the machine are placed as 45 shown in Fig. 1. With the machine in position the space beneath the overhanging arm is sufficient to accommodate the detachable motor control mechanism, which, when not in use, is inserted in a bag Q. The corners of the tray are supported on the flat upper ends 50 of the corner cleats B. The portion of the tray bottom immediately above the position which the machine head H⁴ assumes when the machine is inserted, is removed to permit the 55 upper end of the head to project therethrough. The bottom of the tray at the opposite end of the case is arranged to rest on the flat upper surface of the spool plate K and 60 a small opening P² is formed in the bottom 65

surface to permit the spool post K' to project therethrough.

As illustrated in Figs. 1 and 2, the sides and ends P⁸ of the tray project vertically beyond the upper end of the case body and the tray and case cover are so proportioned that when the cover is in the closed position, the upper edge of the tray side and end members contact with the underside of the top plate C' of the cover. The tray and cover thus cooperate to prevent vertical movement of the machine while in the case and to hold it firmly against the bottom member. This contact action of the tray and cover also aids in preventing horizontal movements of the machine and prevents the various articles carried by the tray from being displaced from their respective compartments. The front plate C² of the cover is cut away at its inner side to permit the cover to pass over the front side 80 of the tray during its movements.

The carrying case of our invention is thus characterized by the simplicity and compactness of its construction and by the effectiveness of its provisions for maintaining a 85 sewing machine in a predetermined position and preventing the latter from injury while in the case. The weight of the case is quite small and in general the weight of the machine and case totals less than twenty pounds. 90

While in accordance with the provisions of the statutes, we have illustrated and described the best form of embodiment of our invention now known to us, it will be apparent to those skilled in the art that changes 95 may be made in the form of the apparatus disclosed without departing from the spirit of our invention as set forth in the appended claims and that in some cases certain features of our invention may be used to advantage 100 without a corresponding use of other features.

Having now described our invention, what we claim as new and desire to secure by Letters Patent, is:

1. A carrying case for a portable sewing machine comprising a rectangular body arranged to receive a sewing machine therein, a rectangular cover connected to said body, and a separate tray positioned in said body and arranged to contact with said machine, said cover being proportioned to hold said tray firmly against said machine when said cover is in its closed position, whereby vertical movements of said machine from a predetermined position are prevented.

2. A carrying case for a portable sewing machine comprising a rectangular body arranged to receive a sewing machine therein, a rectangular cover hingedly connected to said body, and a separate tray supported by said body with the bottom surface of said tray contacting with said machine, said tray and cover being proportioned to contact with one another in the closed position of said cover to 12

- prevent vertical movement of the machine in said case.
3. A carrying case for a portable sewing machine comprising a rectangular body adapted to receive a sewing machine therein, a rectangular cover hingedly connected to said body, and a separate tray supported by said body having side and end members projecting vertically above said body portion and a bottom surface arranged to contact with the upper portion of the machine, said tray and cover being so proportioned that said tray side and end members contact with the underside of said cover in the closed position of the latter.
4. A carrying case for a portable sewing machine comprising a rectangular body adapted to receive a sewing machine therein, a rectangular cover hingedly connected to said body, and a tray supported by said body and having side and end members projecting vertically above said body portion and a bottom surface arranged to contact with the spool plate of the machine, an opening in said bottom surface for the spool post of the machine, and said tray and cover being so proportioned that said tray side and end members contact with the underside of said cover in the closed position of the latter.
5. A carrying case for a portable sewing machine comprising a relatively deep rectangular body having integral vertical side and end wall members and arranged to receive a sewing machine therein, and means for preventing longitudinal movement of said machine in said body during carrying movements comprising a fixed cleat mounted on said body and arranged to contact with and overlap one end of said machine when the latter is in its carrying position.
6. A carrying case for a portable sewing machine comprising a relatively deep rectangular body arranged to receive a sewing machine therein, and having integral vertical side and end wall members, and means cooperating to prevent vertical movement of said machine in said body comprising a fixed cleat secured to one end wall of said body and arranged to fit over a horizontally projecting portion of said machine when the latter is in its carrying position, and means arranged in the opposite end of said body tending to maintain said machine in its proper carrying position.
7. A carrying case for a portable sewing machine comprising a rectangular body having vertical side and end members and arranged to receive a sewing machine therein, and means cooperating to prevent longitudinal and vertical movements of said machine in said body comprising a fixed cleat secured to one end of said body and arranged to fit over a projecting portion of said machine and a fixed block secured to the opposite end of said body and arranged to contact with an adjacent end of said machine when said projecting portion is engaged by said cleat.
8. A carrying case for a portable sewing machine comprising a rectangular body arranged to receive a sewing machine therein, and means cooperating to prevent longitudinal movement of said machine in said body comprising a fixed cleat secured to one end of said body and arranged to contact with a projecting portion of said machine and a fixed block secured to the opposite end of said body and having a smooth convex surface arranged to contact with an adjacent end of the machine while the latter is being placed in position, whereby the latter is held in a predetermined position spaced from an end wall of said body.
9. A carrying case for a portable sewing machine comprising a relatively deep body having integral side and end wall members and arranged to receive a sewing machine of the character described therein, means fixed in said body for removably holding said machine in a predetermined longitudinal position therein, a tray freely positioned in said body on said machine and having openings formed therein arranged to receive projecting portions of said machine, and a cover hingedly connected to said body and arranged to engage said tray when in its closed position to prevent vertical movements of said machine in said body.
10. A carrying case for a portable sewing machine comprising a relatively deep body having integral side and end wall members and arranged to receive a sewing machine of the character described therein, means fixed in said body for removably holding said machine in a predetermined longitudinal position in said body, a shallow tray freely positioned in and contacting with the side and end wall members of said body and having openings receiving projecting portions of said machine, a shallow cover hingedly connected to said body and arranged to engage the top of said tray when in its closed position to hold said machine vertically immovable in said body, and a strap-handle secured to said cover.
- Signed at New York city, in the county of New York and State of New York, this 15th day of May A. D. 1929.
- FREDERICK OSANN.
